Patented Sept. 22, 1914.

UNITED STATES PATENT OFFICE.

ANTON POKORNY, OF MILWAUKEE, WISCONSIN.

FOLDING BOX.

1,111,673.

Specification of Letters Patent. Patented Sept. 22, 1914.

Application filed July 31, 1913. Serial No. 782,216.

To all whom it may concern:

Be it known that I, ANTON POKORNY, a citizen of the United States of America, residing at Milwaukee, in the county of Milwaukee and State of Wisconsin, have invented certain new and useful Improvements in Folding Boxes, of which the following is a specification, reference being had therein to the accompanying drawing.

10 This invention relates to a folding box, and the objects of my invention are, first to provide a collapsible box that will present a rigid structure when set up whereby it can be used for transporting various kinds 15 of merchandise; second a collapsible box that can be constructed on the principle of the crate and used for poultry and fruit; third a collapsible box comprising comparatively few parts that are easy to manipulate 20 when setting up or knocking down the box, fourth a strong, and durable collapsible box that is highly efficient for the purpose for which it is intended. I attain the above objects by mechanical construction to be hereinafter specifically described and then 25 claimed.

Reference will now be had to the drawing wherein:—

Figure 1 is a perspective view of the box 30 in a set up position, Fig. 2 is an end view of the same collapsed, Fig. 3 is a front elevation of the box collapsed, and Fig. 4 is a perspective view of a portion of the collapsed box.

35 A box in accordance with this invention comprises a base plate 1 and connected to the ends of said base plate by hinges 2 are end walls 3 that are adapted to fold inwardly upon the inner side of the base plate

40 1. Connected to the front and rear edges of the base plate 1 by hinges 4 are sectional

side walls, comprising sections 5 and 6 that are hinged together, as at 7. The sectional side walls are adapted to be collapsed upon the bottom side of the base plate 1, as shown 45 in Figs. 2 and 3. A lid 8 is hinged, as at 9, to the upper edge of one of said side walls and said lid can be folded upon the collapsed side walls. The inner sides of the side walls, at the ends and at the upper edges thereof 50 are provided with pivoted hooks 10 to engage in staples 11, carried by the inner sides of the end walls 3 at the upper edges thereof, said hooks and staples constituting means for maintaining the end and side 55 walls rigid and the box in a set up position.

One embodiment of my invention has been illustrated, but it is to be understood that the structural elements are susceptible to such changes as fall within the scope of the 60 appended claim.

What I claim is:—

A folding box comprising a bottom plate, end walls hinged to said bottom plate and adapted to fold inwardly upon the top of 65 said bottom plate, sectional side walls hinged to said bottom plate and having the sections thereof hinged together whereby said side walls can be folded upon the bottom side of said bottom plate, a lid hinged 70 to the upper edge of one of said side walls and capable of being folded upon said collapsed side walls, and hooks and staples in connection with the upper edges of said side and end walls for maintaining a rigid 75 set up box.

In testimony whereof I affix my signature in the presence of two witnesses.

ANTON POKORNY.

Witnesses:

FRANK VALIN,

FRANK SPANIEHEL.
